SELVAGE LOOP RETAINER

Homer F. Roberts, Anniston, Ala.

Application October 1, 1953, Serial No. 383,605

6 Claims. (Cl. 139—195)

This invention relates to a selvage loop retainer for looms and has for an object the provision of a device of the character designated which shall be simple of design, embodying a minimum of parts, easily applied to a loom, and effective in operation, whereby cloth woven on a loom having my invention applied thereto may have filling the same length or longer than the spread of the warp yarn in the reed, and which will lie flat when spread out.

Briefly, my invention comprises a retainer wire suspended from the lay of the loom and passing freely through a guide tube pivotally mounted on the loom temple whereby to rock to and fro responsive to movements of the lay and alternately place the retainer wire alongside the warp ends in position to engage and retain the loop of filling as the shuttle is thrown, and withdraw the wire during beating up movement of the lay.

A particular feature of my invention is the provision of means whereby the loop of filling is engaged by the wire at a slight distance outwardly from the selvage edge of the cloth and the wire, together with the loop of filling, is drawn inwardly toward the selvage by the tension of the filling when the shuttle is thrown. By reason of this provision there is no necessity of doubling the warp ends at the selvage and the cloth at the selvage is no thicker than it is away from the selvage.

Apparatus embodying features of my invention is illustrated in the accompanying drawing, forming a part of this application, in which

Fig. 1 is a side elevational view showing my improved device mounted on the loom temple, with the lay in its extreme backward position, and the retaining wire in position to engage the filling;

Fig. 2 is a similar view showing the lay in extreme forward position with the retaining wire moved out of the path of the filling;

Fig. 3 is a plan view showing the retainer wire in position for engaging the filling; and,

Fig. 4 is a similar view showing the position of the retainer wire after the shuttle has been thrown.

Referring to the drawing for a better understanding of my invention I show a lay embodying a lower frame member 10 and an upper frame member, or reed cap 11, carrying the usual reed 12. At 13 is shown a loom temple which, as is well understood, is mounted upon a stationary part of the loom, not shown. It is also understood that a temple is mounted on each side of the loom and that it is only necessary to show one in order to explain my invention.

Secured to the upper frame member 11 of the lay, by any suitable means, is a guide rod 14, which, as shown, extends parallel with the upper frame member 11 and forwardly thereof. Freely suspended by means of a loop 16, from the guide rod 14, is a retainer wire 17 which, when the lay is in the position shown in Fig. 1 of the drawing, extends downwardly below the level 18 of the cloth in the loom, alongside the selvage ends. The wire 17 extends through a guide tube 19 which is hinged at 21 to a plate 22, secured to the temple by means of the usual temple cap bolt 23. The tube 19 is free to rock to and fro responsive to the to and fro motion of the lay. As shown in Figs. 3 and 4, the guide tube 19 is in the form of a right triangle in cross section, the base of the triangle lying in a plane transversely of the loom and with the hypotenuse of the triangle adjacent the selvage ends 24 in the loom.

Thus, when the guide tube is rocked forwardly by the forward motion of the lay, the inclined side 20 of the tube, when engaged by the retainer wire 17, causes the wire to move laterally to the position shown in Fig. 3 of the drawing. As can be seen from Fig. 3, when in this position, the wire is spaced a slight distance outwardly of the selvage ends 24 and engages the filling 26. When the shuttle is thrown across the loom, the loop of filling 26, engaged by the lower end of the wire 17 is

2

drawn with the wire toward the selvage ends to the position shown in Fig. 4 of the drawing. As the wire 17 is withdrawn to the position shown in Fig. 2 by forward motion of the lay, the filling is drawn in to provide a smooth selvage and a cloth of uniform width.

From the foregoing, it will be seen that the position of the retainer wire 17 is controlled by the position of the guide tube 19 and that the latter is governed by the position of the temple 13. Due to the few moving parts of my improved device, it will be apparent that it may be so set as to provide any desired form of selvage.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim:

- 20 1. In combination with a loom including a lay a temple and a guide rod mounted on the forward side of the lay, a selvage loop retainer comprising a tube pivotally mounted on the temple alongside the warp ends, a retainer wire extending downwardly through the tube, means to suspend the retainer wire substantially vertically from the guide rod when the lay is in its backward position to engage the selvage loop and to be moved upwardly and forwardly away from the warp ends during beating up movement of the lay.
- 25 2. In combination with a loom including a lay a temple and a guide rod mounted on the forward side of the lay, a selvage loop retainer comprising a wire suspended freely from the guide rod alongside the warp ends in position to engage a loop of filling as the shuttle is thrown, a guide tube for the wire pivotally mounted on the temple, said guide tube being triangular in cross section whereby to cause the wire to shift laterally away from the warp ends during beating up movement of the lay and to be moved laterally toward the warp ends when the shuttle is thrown.
- 30 3. In combination with a loom including a lay and a temple on each side of the loom mounted on a stationary part for holding the cloth, a guide rod mounted on the forward side of the lay, a selvage loop retainer comprising a wire suspended freely from the guide rod at each side of the loom rearwardly of the temple in position to engage a loop of filling as the shuttle is thrown, a guide tube for the wire pivotally mounted on the temple and free to rock to and fro responsive to movements of the lay.
- 35 4. Apparatus as defined in claim 3 in which the guide tube is of relatively greater cross section than the wire to permit lateral movement of the wire in the tube during rocking movements of the tube, and in which the tube is triangular in cross section whereby to effect a lateral outward movement of the wire during beating up movement of the lay.
- 40 5. In combination with a loom having a lay with a guide rod mounted on the forward side thereof, and a temple having a burr and a burr housing through which the outside warp ends pass, a tube pivotally mounted on the temple alongside the burr housing, and a retainer wire depending from the guide rod and extending downwardly through the tube alongside the warp ends when the lay is in its backward position and disposed to be moved forwardly and upwardly above the warp ends when the lay moves to its forward position.
- 45 6. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 50 7. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 55 8. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 60 9. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 65 10. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 70 11. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
- 75 12. In combination with a loom including a temple and a lay, a selvage loop retainer comprising a tube pivotally mounted on the temple alongside the warp ends, a retainer wire extending downwardly through the tube, means to suspend the retainer wire substantially vertically from the lay alongside the warp ends when the lay is in its backward position, to engage the filling, and to be moved upwardly and forwardly away from the warp ends during beating up motion of the lay.
